UNITED STATES PATENT OFFICE.

JOHN OLSEN, OF ROLFE, IOWA.

SIGNALING SYSTEM.

1,082,436.

Specification of Letters Patent. Patented Dec. 23, 1913.

Application filed June 21, 1912. Serial No. 705,049.

To all whom it may concern:

Be it known that I, JOHN OLSEN, a citizen of the United States of America, residing at Rolfe, in the county of Pocahontas and State 5 of Iowa, have invented new and useful Improvements in Signaling Systems, of which the following is a specification.

My present invention relates to improvements in signaling systems or apparatus and 10 has particular application to a sending or transmitting apparatus for such systems.

In carrying out this invention, it is my purpose to provide a system of this type wherein sounds may be transmitted from one 15 point to another and high tension currents used to facilitate the transmission of such sounds.

It is also my purpose to provide a signaling system wherein by means of an operating 20 circuit, a signaling circuit may be energized to send out sounds, a novel form of circuit closer being employed in the signaling circuit and actuated from the operating circuit to close the former circuit.

Furthermore, I aim to provide a system 25 of the above-stated character which shall include a circuit closer composed of a rotatable member provided with concentrically arranged conducting and non-conducting surfaces with which may be engaged a contact 30 lever operable from the operating circuit of the system to close the signaling circuit.

With the above and other objects in view, 35 the invention consists in the construction, combination and arrangement of parts hereinafter set forth in and falling within the scope of the appended claims.

In the accompanying drawings; Figure 1 40 is a diagrammatic view of a signaling system embodying the present invention. Fig. 2 is a detail perspective view of the circuit closer, and Fig. 3 is a diagrammatic view of a modified form of the invention.

In the accompanying drawings I have 45 shown my invention as applied to a wireless telephone system. Certain features of the invention, however, are applicable to signaling systems wherein current conducting wires are used, and furthermore the invention 50 is applicable to telegraph systems as well as telephone systems. Therefore, it is to be understood that I do not limit myself to the exact embodiment of the invention as herein shown and described, as I contemplate 55 certain modifications and changes which may be made in order to adapt the in-

vention to the best advantage according to the circumstances or requirements in any particular case.

Similar reference characters designate 60 like parts throughout the several views.

Referring now to the accompanying drawings in detail, my improved signaling system includes an operating circuit A, composed in this instance, of a telephone transmitter 1, an induction coil 2 and the circuit wires 3, a suitable source of energy such as a battery 4 being arranged in the primary of the induction coil, while the secondary circuit is connected to a magnet 5, thus, when 70 sounds are directed into the telephone transmitter the magnet will be energized.

The signaling circuit, in the present instance, is composed of the two circuits so that high tension currents or currents of 75 relatively high voltage may be transmitted to the sparking device, thence to the aerial. Each signaling circuit, in the present instance, comprises the conductors 6 and 7 connected to the primary circuit of a spark coil 80 8 and having one terminal connected to a binding post 9 of the circuit closer C, while the opposite terminal is connected to one pole of a suitable source of electrical energy 85 such as a battery 10, the opposite pole of which latter is connected to one end of a lever of the circuit closer by way of a conductor 11. The secondary circuits of the spark coils 8, 8 are indicated by the numerals 12, 12 and terminate in a sparking device 90 13 embodying a rotary drum or cylinder 14, the latter having connection with an aerial 15 so that upon the energization of the secondary circuits of the spark coils 8, waves 95 may radiate from the aerial.

In order to close the signaling circuit from the operating circuit, I employ a circuit closer which is indicated as an entirety by the letter C. This circuit closer embodies a rotating drum or cylinder 16 composed, in this instance, of the two sections 17 and 18 insulated from each other by means of suitable insulating material designated at 19. These sections are preferably constructed of brass or other suitable conducting material and have their outer extremities circumferentially reduced to provide nipples 20, 20 about which is wrapped hard rubber 21 or the like non-conducting material, such material lying flush with the 105 larger circumferences of the sections so as to present, in effect, a continuous cylindrical 110

surface. Trunnions 22, 22 are formed at the opposite ends of the cylinder 16 and are journaled in bearing brackets 23, 23 mounted upon a base or platform 24 and receiving the binding post 9 of the terminals of the wires 6 of the signaling circuit. The magnet 5 of the operating circuit is also mounted upon this base and is disposed between a pair of contact levers 25, 25 each equipped with an armature 26 and pivoted to the base as at 27, the opposite or free ends of such levers terminating in bifurcated substantially semicircular contacts 28 designed to embrace the cylinder 19. From this, it will be seen that when the magnet 5 is energized, owing to sounds being directed into the transmitter 1, the armatures 26 of the levers 25 will be attracted by the magnet 5 and consequently swing such levers about their pivotal connections 27 and bring the contacts 28 onto the sections 17 and 18 of the cylinder 16 whereby the signaling circuit will be closed, the cessation of such sound permitting the contacts 28 to ride off of the conducting surfaces of the circuit closer and onto the non-conducting surfaces 21 thereof, thus when a succession of sounds are directed into the transmitter, the contact 28 will be engaged alternately with the conducting and non-conducting surfaces of the circuit closer, a suitable form of motor being employed to drive the rotating drum of the circuit closer to facilitate the closing of the signaling circuit, the rotation of the circuit closer drum being approximately synchronous with that of the sparking device.

In the modification of the device disclosed in Fig. 3, I make use of a motor M connected in circuit with a suitable source of electrical energy and equipped with a driving shaft 29 geared to the drums 14 and 16 of the sparking device and circuit closer respectively. Leading from the motor are conductors 30 and 31 terminating in contacts 32, 32 fastened to the platform 34 of the circuit closer, one of such contacts being movable to engage the other and operable from one of the levers 25 of the circuit closer by means of a pin 33 so that upon energization of the magnet 5 from the operating circuit, the motor circuit may be closed to permit the operation of the motor and consequently drive the sparking and circuit closer.

ing drums, a positive and synchronous movement being imparted to such drums 55 from the motor.

While I have herein shown and described one embodiment of my invention, by way of illustration, it is to be understood that I do not confine myself to all of the details of construction herein set forth, as modification and variation may be made within the scope of the claims and without departing from the spirit of my invention.

I claim:

1. A circuit closer comprising a rotating drum formed of two sections insulated from each other and composed of conducting material, rings of non-conducting material surrounding the free ends of said sections, means for supporting said cylinder for rotation, a pair of contact levers each pivoted at one end and equipped with an armature and having its opposite or free end bifurcated to form substantially semicircular contacts designed to embrace the adjacent section of the cylinder and normally resting upon the respective insulated ring, and means for swinging said levers to contact the bifurcated ends thereof with the conducting surfaces of the cylinder.

2. A circuit closer comprising a rotating drum formed of two sections insulated from each other and composed of conducting material, rings of non-conducting material surrounding the free ends of said sections, means for supporting said cylinder for rotation, a pair of contact levers each pivoted at one end and equipped with an armature and having its opposite or free end bifurcated to form substantially semicircular contacts designed to embrace the adjacent section of the cylinder and normally resting upon the respective insulated ring, and a magnet located between said levers and adapted, when energized, to attract the armatures of the levers whereby the latter will be contacted with the conducting surfaces of the drum.

In testimony whereof I affix my signature in presence of two witnesses.

JOHN OLSEN.
